CLAIM

The ornamental design for a rattle, as shown and described.

DESCRIPTION

FIG. 1 is a perspective view of a rattle showing our new design;

FIG. 2 is a left elevational view thereof;

FIG. 3 is a right elevational view thereof;

FIG. 4 is a front elevational view thereof;

FIG. 5 is a rear elevational view thereof;

FIG. 6 is a top plan view thereof; and,

FIG. 7 is a bottom plan view thereof.

The dashed lines are included for the purpose of illustrating the portions of the rattle that form no part of the claimed design.
